CLAIM

The ornamental design for a food container assembly, as shown and described.

DESCRIPTION

FIG. 1 is a top and front perspective view of a food container assembly showing our new design;

FIG. 2 is a top plan view thereof;

FIG. 3 is a bottom plan view thereof;

FIG. 4 is a right side elevation thereof;

FIG. 5 is a left side elevation thereof;

FIG. 6 is a rear elevation thereof;

FIG. 7 is another top perspective view of thereof with the lid removed;

FIG. 8 is a top plan view thereof;

FIG. 9 is a bottom plan view thereof; and,

FIG. 10 is a side elevation thereof, the other sides being identical.

The unshown underside of the lid for the food container assembly forms no part of the claimed design.
